UNITED STATES PATENT OFFICE

100,454

DESIGN FOR A COMBINED ASH, TOBACCO, AND MATCH RECEPTACLE

Leonard L. Hayes, Des Moines, Iowa

Application March 23, 1936, Serial No. 61,747

Term of patent 3½ years

To all whom it may concern:

Be it known that I, Leonard L. Hayes, a citizen of the United States, residing in Des Moines, in the county of Polk and State of Iowa, have invented a new, original, and ornamental Design for a Combined Ash, Tobacco, and Match Receptacle, of which the following is a specification, reference being had to the accompanying drawing, forming a part thereof.

The figure is a front perspective view of a combined ash, tobacco, and match receptacle, showing my new design.

I claim:

The ornamental design for a combined ash, tobacco, and match receptacle, substantially as shown.

LEONARD L. HAYES.
